PACKAGE BINDING TOOL

George A. Crosby, Park Ridge, and Arvid I. Ericsson, Chicago, Ill., assignors to Signode Steel Strapping Company, Chicago, Ill., a corporation of Delaware

Application December 15, 1948, Serial No. 65,448

11 Claims. (Cl. 140—93.4)

1

Our invention relates to package binding tools. More specifically it relates to a tool particularly adapted for use in binding relatively soft or fragile packages, which is operable to hold the overlapping ends of a package encircling flexible metallic binder in aligned relation and tension the same to the proper degree, whereupon the tool is operable to place a seal upon the overlapping ends of the package encircling binder loop and deform the same to produce a seal-joint, permanently anchoring together the binder ends, and thereafter the tool is operable through a further stage for transferring a seal from a magazine to the sealing jaws of the tool to condition the tool for another sealing operation.

In the normal operation of a tool of this type, a considerable amount of force must be applied thereto in forming the seal-joint. Heretofore this force was transmitted, through the base of the tool, to the package being bound so that relatively fragile packages might be crushed and soft or easily compressible packages might not afford adequate resistance properly to support the tool, at least not without objectionable distortion. In addition to this disadvantage of the tools of the prior art, difficulty is sometimes encountered with the seal feeding mechanism in that a seal becoming accidentally jammed in the magazine cannot be as readily removed as might be desired.

The tool of the present invention is constructed in part from a lightweight metal alloy, thus reducing its total weight so that it does not bear as heavily on the package being bound and is less fatiguing to handle. In addition to a conventional operating handle it is provided with a reaction handle against which a force may be exerted when a seal-joint is being formed sufficient to counterbalance the force exerted on the operating handle so that relatively little if any operating force needs be transmitted to the package being bound. Thus the tool is especially adapted for binding relatively soft or fragile packages. Also incorporated in the tool are an improved binder strap aligning lever for holding the overlapping ends of the package binder in proper relation while they are being tensioned, and an improved seal magazine and simplified seal ejector, all of which tend to obviate the disadvantageous features above mentioned which may be more or less inherent in package binding tools as presently manufactured.

Accordingly, an object of the invention is the provision of a new and improved package binding tool which is particularly adaptable for use in binding relatively soft or fragile packages.

2

Another object of the invention is the provision of a new and improved package binding tool having an operating handle operable to both tension a package encircling binder and to form a joint in the overlapping ends of the tensioned package-looping binder, and a reaction handle through which a force may be exerted to counterbalance the force exerted on the operating handle during the sealing operation and thereby prevent the operating force from being transmitted to the package being bound.

A further object of the invention is the provision of a new and improved package binding tool incorporating a magazine for the storage of seals used in forming a joint between the overlapping ends of a package encircling binder strap having guide means formed at its outlet and for guiding seals into the sealing mechanism of the tool when the seals are being transferred from the magazine to the sealing mechanism.

A still further object of the invention is the provision of a new and improved package binding tool having an outlet (in the magazine as above set forth), one wall of which is hinged to permit pivotal movement of the same from seal engaging position so that a seal jammed in the outlet may be readily removed therefrom.

Yet another object of the invention is the provision of a new and improved package binding tool having a magazine as above set forth and an improved ejector for transferring seals from the outlet of the magazine to the sealing mechanism of the tool operable through the medium of a cam on the operating handle of the tool, and an adjustable connection between the cam and ejector for varying the throw of the ejector so that the latter will be held in a position preparatory to transferring a seal until the operating handle has been moved sufficiently to condition the sealing mechanism for receiving a seal.

Still another object of the invention is the provision of a new and improved package binding tool having a binder tensioning mechanism movable into and out of binder engaging position, and an improved binder aligning lever for engaging the edges of the overlapping ends of a package binder to hold the same in aligned relation while they are being tensioned, which lever is adapted to be moved into and out of binder engaging position simultaneously with the movement of the tensioning mechanism into and out of binder engaging position.

A further object of the invention is the provision of a relatively inexpensive lightweight tool of the class described of generally improved and

simplified construction which is positive in operation and simple and easy to manipulate.

Other objects, advantages and capabilities of the invention will become apparent from the following description of a preferred embodiment thereof taken in conjunction with the accompanying drawings, in which:

Fig. 1 is an elevational view of one side of the tool showing in full lines the position of the parts when the tool is at rest and indicating, in dot-dash lines, the position of the operating parts at the beginning of a joint forming or sealing operation;

Fig. 2 is an elevational view of the side of the tool opposite that of Fig. 1, showing the parts in the position they assume when a joint is completed;

Fig. 3 is a vertical section of the tool in normal position;

Fig. 4 is a section on the line 4—4 of Fig. 3;

Fig. 5 is a section on the line 5—5 of Fig. 3; and

Fig. 6 is a fragmentary front elevation with the base of the tool in section showing the binder aligning lever in inoperative position.

For the purpose of explanation the improved features of the present invention have been shown and will be described as incorporated in a combined binder-tensioning and sealing tool of the same general type as that set forth in Patents Nos. 2,336,264 and 2,267,612, both issued to John H. Leslie, II.

Referring particularly to Figs. 1, 2 and 3, the tool comprises a main frame A which is adapted to rest upon the package being bound and pivotally supports a binder-tensioning mechanism B and an oscillatable auxiliary frame C. The auxiliary frame carries a sealing or joint forming mechanism D, a seal magazine E and a seal feeding mechanism F for feeding seals from the magazine into the sealing mechanism. An operating handle G is pivotally secured to the auxiliary frame C. This handle is adapted to be oscillated through a first range of movement during which the auxiliary frame moves with it for actuating the tensioning mechanism B; then handle G may be pivoted beyond the first range of movement to bring the sealing mechanism into position over the overlapping ends of the tensioned package-looping binder strap and thereafter it may be forced through a further or third range of movement to cause the sealing mechanism D to be actuated to form a joint uniting the overlapping ends of the package encircling binder loop. Finally the handle G is returned to effect the feeding of a new seal to the sealing mechanism D and to return the auxiliary frame C to its normal or rest position.

The main frame A, which may be formed from an aluminum alloy casting, is provided with a flat bottom surface 10 for resting on the package which is to be bound and has an integrally formed handle 12 to strengthen the main frame and facilitate the handling of the tool. At its forward end this handle 12 merges into a wall 14 extending vertically from the base portion of the main frame and a vertical flange 15 spaced from and parallel to the wall 14. The auxiliary frame C projects into this recess between wall 14 and flange 15 and is pivoted to the main frame by a bolt 16 which extends through the wall and flange. The flange 15 is also separated from the front portion of the base of the main frame by a longitudinally extending channel 18 between the flange and the top surface 20 of a laterally extending front foot 22, which foot forms the front

end of the base of the main frame A. This foot has an opening 24 adjacent the front end thereof into which the outer end of the sealing mechanism D projects when the sealing mechanism is moved to joint-forming position over the overlapping ends of a package encircling binder strap, as will be later explained.

In the normal use of the tool a binder strap is looped around a package and the tool is placed in position on the package by sliding the front foot 22 laterally under the overlapping ends of the binder loop so that these overlapping ends are positioned in the channel 18 and below the binder-tensioning mechanism B. Ordinarily, the tool is so placed that the anchored end of the binder loop will be on the bottom and will extend to the right, as seen in Fig. 1, while the unsevered and movable end of the binder loop is on top and extends to the left, as seen in Fig. 1.

A hard metal clutch plug 26 (preferably crowned toward the center as best shown in Fig. 3) having a knurled upper surface for engaging the under surface of the bottom overlapping end of the binder strap loop is threaded into the foot 22 so as axially to align with the vertical axis of the tensioning mechanism B when in operative position. This plug, which is threaded for adjustment relative to the tensioning mechanism, may be locked in any adjusted position by a wire lock or other conventional means. During a tensioning operation it holds the bottom overlapped end of the binder loop stationary while the upper overlapping end is moved to the left, as seen in Fig. 1, by the tensioning mechanism B to tighten the loop around the package.

In order to insure the proper alignment of the overlapping ends of the binder strap, a metal guide plug 28 is secured in the side wall 14 of the main frame A adjacent the rear end of the channel 18 and a front strap guide 30, in the form of a notched plate, is secured on the forward end of the front foot 22 by means of screws 31 countersunk into the plate 30 and threaded into the base 10 of the main frame, as shown most clearly in Fig. 3. The strap ends are held in aligned relation against these rear and front guides, while the binder is being tensioned, by means of an improved binder strap aligning or guiding lever 32, best seen in Fig. 6. Strap guide 30 has a projection or lip 33 which overhangs the inner edge of the strap to prevent undue strap separation in front of the tool.

As shown in Figs. 3 and 6, this strap aligning lever, which extends transversely of the foot 22, is pivotally secured at one end in a slot 34 formed in an upwardly extending lug 36 cast integrally with the base of the main frame A. The lug 36 is located forward of the axis of the tensioning mechanism B so that operation of the latter is not interfered with by the aligning lever 32 and the lever pivots upon a pin 38 which extends horizontally through it and the lug 36. This pin has a head on one end and a cotter pin may be inserted through an opening in the other end where it extends through the lug 36 to prevent the pin from coming out of position.

The bottom surface of the lever 32 forms a straight edge for a portion of its length as indicated at 40 and this straight edge terminates in a depending shoulder 42 and an outwardly extending portion 44 having a bottom edge lying below the plane of the straight edge 40. When the lever 32 is lowered to operative position this portion 44 enters a slot 46, formed in the top of the foot 22, and while the edge 40 engages the top sur-

face of the upper overlapping binder end, the shoulder 42 engages the outer edges of the overlapping binder ends at a point midway between the front and rear guides. Thus, it will be seen that the overlapping binder ends are held in alignment against the aligning plug 28 and guide 30 during a tensioning operation. A lip 48 is formed on the outer end of the lever 32 and is bent rearwardly into a horizontal plane, as shown in Fig. 1. The function of this lip 48 and the means for moving the lever 32 into an out of operative position and for locking it in these positions will be later described.

The auxiliary frame C and tensioning mechanism B are pivoted to main frame A by means of bolt 16 essentially in the manner disclosed in the beforementioned Leslie patents, the tensioning mechanism being secured upon an eccentric portion of the bolt (indicated at 52 in Fig. 3) so that by turning the bolt in a counterclockwise direction the tensioning mechanism is lowered and brought into engagement with the top overlapping strap end over the central portion of the clutch plug 26. And by turning the bolt 16 in a clockwise direction the tensioning mechanism can be raised out of engagement with the upper binder strap end.

The bolt 16 is normally biased in a counterclockwise direction to move the tensioning mechanism to operative position by means of a coil spring enclosed in a housing 54. This construction is fully described in Leslie Patent No. 2,336,264 and, therefore, will not be shown or described in detail herein. An actuating handle 56, which has a cam 58 nonrotatably secured on the end of the bolt 16 opposite the spring housing 54, is provided for rotating the bolt in a clockwise direction against the tension of its biasing spring and thereby raise the tensioning mechanism out of operative or strap engaging position. The shank 58 is secured to the bolt 16 by means of a cap screw 60 threaded into a tapped bore in the bolt 16. The bolt is locked at the limit of its clockwise movement by a latch 62 pivotally secured to the main frame A upon a pin 64 secured in the flange 15 of the main frame, as shown most clearly in Fig. 1. This latch 62 is normally urged to handle locking position as shown in Fig. 1 by a spring 66 located in a curved opening 68 in the latch and bearing at its lower end against a fixed abutment to be hereinafter described and at its upper end against the upper end of the opening 68 so that the spring urges the latch 62 in a counterclockwise direction. The limit of the movement of latch 62 in the counterclockwise direction is determined by the engagement of the lower end of the opening 68 with the fixed abutment.

In the raised position of latch 62 a notch 70 in its forward edge is adapted to engage with a pin 72 secured on the inner side of the cam 58 of the handle 56 but only when the latter is turned to the limit of its movement in a clockwise direction to raise the tensioning mechanism to inoperative position. Notch 70 is so formed that it firmly grips the pin 72 and causes latch 62 to lock the handle 56 in this position against the tension of the biasing spring acting on bolt 16. The latch 62 may, however, be disengaged from the pin 72 to release the handle 56 by the operator pressing downwardly on the outer end of an arm 74 which extends rearwardly from the body of the latch. Thereupon the biasing spring rotates bolt 16 in a clockwise direction and lowers the tensioning mechanism B to operative position

and in addition lowers the aligning lever 32 to operative position and locks the same in this position as will now be described.

Along its edge opposite handle 56, the cam 58 is formed with a notch 76 below which the cam projects as a lug 78. Normally, when handle 56 is locked in its extreme clockwise position by latch 62 and the tensioning mechanism is thereby held out of strap engaging position as shown in Figs. 10 and 6, notch 76 opens rearwardly and substantially horizontally and lug 78 engaging lip 48 holds strap aligning lever 32 raised above foot 22. But when the handle 56 is released from latch 62 to enable the tensioning mechanism B to move to operative strap engaging position, the cam 58 is rotated counterclockwise sufficiently to cause the upper wall of its notch 76 to engage lip 48 of aligning lever 32 and rotate that lever far enough to depress its depending portion 44 into the slot 46 in forward foot 22. In this position the shoulder 42 of lever 32 engages the edges of the overlapping strap ends to insure that they remain in proper horizontal alignment, as previously explained. A shoulder 80 is also formed on cam 58 at such a location that it engages the top surface of the lip 48 on lever 32 when the handle 56 is rotated to its extreme counterclockwise position and, as a consequence, lever 32 has been depressed into position to close channel 18 and to align the overlapping strap ends, and thereby the strap aligning lever 32 is locked in closed or strap aligning position as long as the tensioning mechanism is in strap engaging position.

35 The tensioning mechanism B comprises a pair of feed wheels 82 secured on either side of a ratchet wheel 84. This assembly is rotated by an actuating pawl 86 secured in the auxiliary frame C upon a pin 88 extending between and secured 40 against removal from the side walls of the auxiliary frame by any suitable means. The pawl 86 is held in engagement with the teeth 90 on the ratchet wheel 84 by a spring 92. When the auxiliary frame C is rotated in one direction, e. g., clockwise as seen in Fig. 3, the pawl 86 engages in the ratchet teeth 90 and rotates the feed wheels 82 in a clockwise direction, thereby effecting movement of the upper strap end of the binder loop over the lower strap end which is held stationary on the clutch plug 26 in the front foot 22. A holding pawl 94 is pivoted to the main frame A upon a pin 96 extending transversely through the base of the main frame. This pawl engages the teeth 90 of ratchet wheel 84 and prevents reverse rotation of the feed wheels 82 during counterclockwise rotation of the auxiliary frame B. The outer end of this pin 96 extends through the opening 68 in the body of latch 62 and thus forms a guide for the movements of the latch and also the abutment against which one end of the spring 66 rests, as previously described.

65 The auxiliary frame C is provided with an operating handle 98 which is pivotally secured thereto by a shouldered pivot pin 100 and also with a reaction handle 102 rigidly secured thereto by means of a pair of pins 104. The operating handle 98 may be cast from an aluminum alloy and has a channel 106 along its underside in which the reaction handle is adapted to nest, as shown in Fig. 3. The forward end of the operating handle 98 is formed with a pair of flanges 108 spaced sufficiently so that they straddle the auxiliary frame. The enlarged portion of the 70 shouldered pivot pin 100 extends through one

flange 108 and the auxiliary frame C and the shoulder thereon abuts against the other flange 108 while the reduced portion extends through this latter flange. A nut 110 is threaded on this reduced end to lock the pivot pin in position.

The operating handle 98 may, when desired, be retained to move in unison with both the auxiliary frame C and reaction handle 102. This retention is accomplished by a spring pressed latch 112 which, as shown in Fig. 3, is pivotally carried upon a pin 114 secured in the auxiliary frame C. A notch 115 in latch 112 is engageable over a cross pin 118 which extends between and is fixedly secured in the flanges 108 on the operating handle. The latch 112 is biased by a spring 120 in a direction to cause notch 115 to engage pin 118 with considerable pressure but, because of its configuration, the pin can be forced out of the notch and the latch disengaged when a pressure greater than that required to oscillate the auxiliary frame C and operate the tensioning mechanism B is exerted on handle 98. When the latch 112 is engaged with the pin 118, it holds the handle 98 in fixed relation with the auxiliary frame C and the reaction handle 102, as shown in Figs. 1 and 3, and movements of the operating handle effects like movements in the auxiliary frame and reaction handle. But, when the handle 98 has reached the limit of its first range of movement in a counterclockwise direction to bring the sealing mechanism D down to the overlapping strap ends, as shown in dot-dash lines in Fig. 1, further effort exerted on the handle 98 in a counterclockwise direction to actuate the sealing mechanism causes the latch 112 to become disengaged from the pin 118. The result is that the handle 98 may be pivoted through a second range of counterclockwise movement upon the pivot pin 100, and independently of both the auxiliary frame and the reaction handle, to cause the sealing mechanism D to be operated and form a joint in the overlapping ends of the binder strap. Upon its return or clockwise movement from the limit of this second range of movement, the operating handle 98 causes the seal feeding mechanism F to load a seal in the sealing mechanism D, thereby conditioning the tool for another sealing operation, as will be later explained.

The reaction handle 102 is somewhat shorter in length than the operating handle and is fixedly secured at one end to the auxiliary frame C as before mentioned. On its under side the lever 102 is provided with a downwardly extending stop lug 122 adapted to engage the top of the main frame A to limit movement of the handles and auxiliary frame in a clockwise direction.

It will be apparent that in the conventionally constructed tensioning and binding tools the force exerted on the operating handle when the latter is moved through its second range of movement to form a joint in the overlapping binder strap ends is transmitted to the package being bound through the base of the tool. This force, which is normally more than required for binder tensioning, may be of such magnitude that anything but relatively heavy and substantial packages will be deformed or crushed by the tool. This disadvantage of binding tools as presently constructed is obviated in the tool of the present invention through the use of the reaction handle 102. When the operating handle 98 is pivoted in a counterclockwise direction beyond its first range of movement, i. e., from the position shown in dot-dash lines in Fig. 1 to the position shown in Fig. 2 at which point formation of a joint has

been completed, the reaction handle and auxiliary frame remain stationary so that the operating handle moves away from the reaction handle and a force may be exerted on the latter by the operator in a clockwise direction to balance or counteract the force exerted on the operating handle 98. These two opposing forces, one toward the package being bound and the other away from it, can be made such by the operator that they substantially counterbalance each other and no appreciable operating force, or at least none of destructive intensity, need be exerted on the package.

The sealing mechanism D for placing a seal over the overlapping ends of a package-encircling binder loop and forming a joint therein is carried on the auxiliary frame C between the wall 124 thereof and a sealer plate 126 spaced from the wall 124 by a pair of spacers 128, one of which is located on each side of the auxiliary frame adjacent the rear end thereof. The forward end of the sealer plate 126 is fixedly secured in position by a bolt 130 which is threaded into the wall 124 of the auxiliary frame C. The rear end of the sealer plate 126 engages between the upper end of the spacing collars 128 and the underside of the bottom wall of the seal magazine E. This rear end of the assembly is secured together by a pair of screws 132, Fig. 5, one on each side of the auxiliary frame C. These screws have heads seated in counterbored openings in laterally extending bosses 134 on the upper edge of the auxiliary frame C, and the screws extend through the spacers 128 and the plate 126 and are threaded into laterally extending bosses 136 on the bottom wall of the magazine E aligned with the bosses 134.

Within the space between the top of the auxiliary frame C and the sealer plate 126 are secured a pair of opposed holding jaws 138 for preventing buckling of a seal when a joint is being formed, and a pair of opposed sealing jaws 140, one pair on each side of the holding jaws, for deforming the seal and overlapping strap ends to form a joint and the actuating mechanism for operating these jaws.

Referring to Fig. 5, it will be seen that the sealing and holding jaws have forward inwardly projecting tips 142 and that the sealing jaws 140 have, rearwardly or inwardly of these tips, crimping lugs 143. The jaws pivot upon fixed fulcrum pins 144, but the rear ends of the sealing jaws 140 are extended backwardly beyond the rear ends of the holding jaws 138, these rear ends of the holding jaws being fixed with respect to the sealing jaws 140 through the agency of a pair of pins 146 extending between the sealing jaws and through the ends of the holding jaws 138 so that the latter are fixed with respect to and move with the sealing jaws 140. The upper ends of these pins 146 project beyond the top surface of the upper sealing jaws for a purpose which will be described hereinafter. The sealing jaws 140 are spaced from the holding jaws 138 by a pair of plates 148, Fig. 3, secured in fixed relation upon the fixed fulcrum pins 144. The forward edges of these spacer plates 148 act as an anvil for pressing a seal into position over the overlapping ends of a binder strap loop when the sealing mechanism is moved to joint forming position and assist in preventing buckling of the seal when it is deformed in the formation of a joint.

The rear ends of the sealing jaws are pivotally secured to one end of a pair of jaw actuating

links 150 by means of fulcrum pins 152. These ends of the jaws embrace the ends of the links to which they are secured and the portion of the pins 152 passing through the links 150 is of enlarged diameter relative to the ends which engage in the ends of the jaws 140 so that these pins will not drop from position when the tool is in use. The other ends of the links 150 are located in a slot 154 in a slidable crosshead 156 and pivoted to the crosshead by means of a pivot pin 158. Since the opposite ends of this pin engage the top of the auxiliary frame and the sealer plate 126 respectively, the pin 158 cannot fall from position when the tool is assembled.

As previously indicated, the sealing jaws 140 are actuated to form a joint during the course of the second range of counterclockwise movement of the operating handle 98 when the latter pivots with respect to the auxiliary frame C. This actuation is effected through an operating link 160 secured at one of its ends upon a drive pin 162 extending through the upper ends of the flanges 108 on the operating handle 98. The other end of the link 160 is engaged in a vertical slot 164 in crosshead 156 and pivotally secured thereto by an eccentric pin 166. This pin 166 is engaged and locked in position by a set screw 168 threaded into an opening in the link.

Slidable upon the top side of the sealer plate 126 adjacent its forward end is a cutter blade 170. This blade has a tapered and hardened cutting edge 172 which is moved into engagement with the upper overlapping end of a binder strap and scores the same while a joint is being formed so that the binder may be easily broken along this score line by bending it back and forth a few times. At its rear end the cutter blade has outwardly extending wings 174, Fig. 4, with transverse sockets 176 formed therein, and the blade is secured in position in a channel 178 between the bottom of the magazine E and the top of the sealer plate 126 with the sockets 176 engaged over the upper extremities of the pins 146 so that the outward and downward movement of these pins during the actuation of the sealing mechanism to form a joint will be translated into downward movement of the blade.

When the operating handle 98 is pivoted through its second range of counterclockwise movement from the position shown in dot-dash lines in Fig. 1 to the position shown in Fig. 2, the link 160 moves the crosshead 156 downwardly from the position shown in Fig. 5 and the links 150 cause the rear ends of the two pairs of sealing jaws 140 to separate, thereby moving the faces 142 of these jaws toward each other and causing the scoring blade 170 to move downwardly and score the binder strap. The links 150 exert a toggle action on the jaws, thereby greatly increasing the force exerted thereon so that a relatively small movement of the crosshead 156 causes the jaws 140 to bend a seal around the strap ends and as the crosshead moves further down the faces of the jaws deform the seal and overlapping strap ends to form a permanent joint therein.

After a joint has been formed and during the course of the return of the handle 98 from joint forming position to the position shown in dot-dash lines in Fig. 1, the crosshead 156 is moved upwardly by the link 160 and draws the upper ends of the links 150 upwardly, thus pulling the rear ends of the jaws 140 toward each other and causing the jaws to pivot upon pins 144 so that the faces 142 of the jaws separate. At the same time the scoring blade 170 is retracted. Before

the operating handle 98 is fully returned from its second range of movement to the position shown in dot-dash lines in Fig. 1, the faces of the sealing jaws 140 have separated sufficiently to release the binder so that the sealing mechanism can be moved away from its joint forming position.

In general, the seal magazine is a box-like structure open at both ends and is preferably cast from aluminum alloy. It has a bottom wall 180, side walls 182 and 184, Fig. 4, a top wall 186, and an open outlet end 188. The inner surfaces of these walls are machined to form smooth guideways for a follower 190 which is slidable therein and engages against the top seal in a stack of seals 192 carried in the magazine. This follower 190 is normally urged toward the lower or outlet end of the magazine by a spring 194 housed in a hollow boss 196 projecting outwardly from the side wall 184 near the magazine outlet 188. The spring is wound on a spindle 198 extending into the boss 196 and one of its ends is secured to the spindle 198 while the other end is drawn out of the housing 196 and secured to the follower 190 so that a pull toward the magazine outlet is exerted by the spring on the follower 190. As a result the seals in the magazine are urged toward the outlet end 188.

These seals 200 which are made from easily deformable sheet metal are generally channel shaped in cross section, as indicated in Fig. 5, but the sides or flanges 202 flare outwardly slightly from the back so that the seals may be stacked in nested relation, but the backs of adjacent seals will be held in slightly spaced relation with respect to each other, as shown in Fig. 4. This permits the forwardmost seal in the stack 192 to be stripped therefrom by movement in an endwise direction without disturbing other seals in the stack. Thus, when the feeding mechanism is actuated in a feeding direction it moves only the foremost seal in the stack 192 in an endwise direction so that the seals may be fed one at a time by the feeding mechanism.

Occasionally a seal may become jammed in the outlet of the magazine. Heretofore such jammed seals were difficult to remove. A feature of the tool of the present invention is the means provided for the removal of jammed seals. Referring to Figs. 1 and 4, it will be seen that the side wall 182 of the magazine E terminates short of the outlet end 188 of the magazine. This open portion of the wall is closed by a trap door 204 pivotally secured upon a pin 206 having its opposite ends seated in openings in the bosses 208 and 210 formed on the top and bottom walls respectively of the magazine. A spring 212 is wound on this pin 206 and has one end engaged against the side wall 182 of the magazine and the other end engaged against the side of the trap door 204 so that the latter is urged to closed position by this spring. Adjacent its lower inner edge the door 204 is provided with a longitudinally extending ledge 214. A similar ledge 216 oppositely disposed to the first is formed in a removable guide 218 secured to the fixed wall 184 of the magazine by a pair of countersunk screws 220. These ledges 214 and 216 project inwardly toward each other sufficiently so that the edges of the side walls 202 of the foremost seal in the magazine engage the ledges. Thus, the ledges act as a stop to prevent the seals from being expelled from the magazine by the spring pressed follower 190 and in addition act as guideways for guiding a seal for movement in an endwise di-

rection into the jaws of the sealing mechanism D. The ledges 214 and 216 are of course properly positioned so that a seal is correctly guided into the sealing mechanism.

Should a seal accidentally become jammed in the outlet, the trap door 204 may be pivoted outwardly on the pin 206 against the tension of the spring 212 a sufficient distance to disengage the ledge 214 from the edge of the forward seal in the stack. Ordinarily, the jammed seal may then be readily removed from the magazine by sliding it out in a lateral direction. While this is being done, the stack 192 is held in the magazine against the ledge 216 on the fixed wall of the magazine so that the entire stack is not expelled from the magazine when the door 204 is pivoted outwardly. To facilitate pivoting of the door 204 a handle 222 is provided thereon extending upwardly from the door. This may be pressed inwardly when it is desired to open the door.

In addition to the advantages above described the pivoted door also permits the magazine to be loaded by inserting a stack of seals from the forward or outlet end of the magazine without the necessity for removing the follower therefrom. The door 204 is merely held in open position and a stack of seals 192 inserted in the magazine and forced backwardly until the edge of the last seal in the stack is in position to engage upon the ledge 216. The stack is then held in position and the door 204 released to bring the ledge 214 into engagement with the opposite edge of the foremost seal.

The seal ejector actuator for operating the ejector which strips seals from the stack 192 and moves them into the sealing mechanism comprises a generally L-shaped aluminum alloy casting 224 which is pivotally secured intermediate its ends to a pair of lugs 226 upstanding from the top wall 186 of the magazine adjacent the rear end thereof. This actuator pivots upon a pin 228 and is normally urged in a seal ejecting direction to the position shown in Figs. 1 and 3 by a relatively heavy spring 232 coiled upon the pin 228. One end of this spring bears against the top wall 186 of the magazine while the other end bears against the horizontal portion of the ejector actuator 224 and exerts a force thereon tending to move the same to the position shown in Figs. 1 and 3.

The ejector proper comprises an elongated blade 234 pivotally secured at one end upon a pin 236 carried in a head 238 on the tip of an arm 240 forming part of the ejector actuator 224. The blade 234 is slightly bowed and is provided with a stripper tip 242 bent inwardly at a slight angle to insure its engagement with the edge of the body of the foremost seal 200 in the magazine E. A tension spring 244 coiled about the pin 236 and having its opposite ends engaged with the arm 240 and the blade 234 urges the latter in a direction to bring the stripper tip into engagement with the end of a stop screw 246 threaded into the end of the top wall of the magazine centrally thereof. This screw 246 projects sufficiently so that the stripper tip 242 engaging thereon will be located directly opposite the edge of the body of the foremost seal in the magazine when the ejector actuator draws the ejector blade outwardly to a preparatory position for ejecting a seal from the magazine, as shown in Fig. 2.

The ejector actuator is rotated to this position by means of a sector shaped cam 248 which engages with an adjustable stop screw 250 thread-

ed in the end of a bellcrank arm 252 formed integrally with the actuator. This screw may be locked in a desired position of adjustment by a lock nut 254. The cam 248 is secured upon the outer reduced end of the operating handle pivot pin 100 with the axis of its curved edge coinciding with the axis of the pin 100, and it is locked against rotation by the pin 162 which passes through the cam 248 and the flanges 108 of the operating handle and connects the operating link 160 to the handle 98. Thus, it will be seen that the cam 248 and operating handle 98 pivot together when the handle is moved about pin 100.

When the operating handle 98 is moved through its first range of movement the auxiliary frame C oscillates with it, as previously explained, and the cam 248 remains in fixed position with respect to the ejector actuator 224. However, when the operating handle 98 is actuated further and enters upon its second range of movement, the cam 248, being fixedly secured to the operating handle, pivots with this handle. It is so fixed with relation to the tip of screw 250 that upon initiation of movement of the operating handle 98 into its second range of movement a straight radial face 256 on the cam is moved into engagement with the tip of the screw 250. As movement of the handle 98 is continued this face is moved in a clockwise direction, as seen in Fig. 2, and exerts a force on the tip of screw 250 tending to rotate the ejector actuator in counterclockwise direction upon the pin 228 against the tension of spring 232. This movement of the ejector actuator continues until the handle 98 and cam 248 are advanced sufficiently to bring the curved peripheral edge 258 of the cam 248 into engagement with the tip of screw 250. At this time the ejector actuator has been rotated sufficiently to carry the stripper tip 242 of the ejector blade 234 to a position opposite the edge of the back of the forward seal in the magazine E. During further advancing movement of the operating handle 98 the curved peripheral edge 258 of the cam 248 rides upon the tip of the screw, but since this surface is concentric with the pivotal axis of the cam 248 no further movement of the ejector actuating mechanism occurs and it is held stationary with the ejector in cocked position until return movement of the handle has progressed sufficiently to again bring the straight radial face 256 of the cam opposite the tip of screw 250. As return movement of the handle 98 is continued, the spring 232 acting on the actuator 224 pivots the same so that the stripper tip 242 of the ejector blade 234 is brought into engagement with the edge of the last seal in the magazine and moves this seal out of the magazine until its lower edge engages the top surface of the partly opened upper sealing jaws 140. When return movement of the handle 98 has progressed to the point where the working faces of the jaws 140 open sufficiently to receive the flared edges of a seal 200 therebetween, the partly ejected seal is suddenly propelled or snapped into position in the jaws by the action of spring 232 on the actuator 224. The body of blade 234 engages in and extends across the channel in the last seal in the magazine when such a movement has been completed, thus tending to aid in holding seals in the magazine against accidental release.

Briefly reviewing the operation of the tool, it will be assumed that a binder strap has been looped about a package, that the tool is resting upon the package and that, either by lateral

movement of the tool or of the overlapping strap ends, those overlapping ends of the binder loop have been caused to lie in channel 18 between the feed wheels 82 and the underlying clutch plug 26. The operator then presses on the arm 74 of latch 62, thereby releasing actuating handle 56 and bolt 16 for rotation in a counterclockwise direction as a result of the torque exerted on the bolt by the spring housed in cap 54. This rotation of the bolt 16 lowers the feed wheels 82 into contact with the upper of the overlapping strap portions. At the same time rotation of the cam 58 of handle 56 releases the aligning lever 32 so that its straight edge 40 engages the top surface of the upper of the overlapping strap portions and the shoulder 42 engages the outer edges of both strap ends. The aligning lever 32 is locked in this position by the shoulder 80 on the cam 58 of the actuating handle 56 engaging the top of lug 48 on the aligning lever.

The tool is now in condition to tension the binder loop and this is accomplished by oscillating the operating handle 98 through an arc which extends upwardly, as a maximum, to an approximate vertical, as shown in dot-dash lines in Fig. 1. The auxiliary frame C is oscillated with the operating handle 98 through this first range of movement because the latch 112 remains engaged with the fixed cross pin 118. These oscillatory movements of handle 98 causes the actuating pawl 86 to rotate the feed wheels 82 step-by-step to move the upper binder end past the lower binder end and thereby tension the binder. During these operations the magazine E, sealing mechanism D and the reaction handle 102 oscillate with the auxiliary frame and the operating handle but perform no function.

When the desired tension in the binder loop is attained the handle 98 is swung in a counterclockwise direction to the upper limit of its first range of movement indicated in Fig. 1 to carry the sealing jaws 140 into overlapping relation with the portion of the overlapping ends of the binder loop in which the joint is to be made, as indicated by the dot-dash lines of Fig. 1. This brings the seal 200 which was fed into position between the jaws in the previous operation into a position where it partly encircles the overlapping strap ends.

Upon further movement of the operating handle 98 in counterclockwise direction the latch 112 becomes disconnected from the cross pin 118 and the handle 98 pivots upon the pin 100 as an axis instead of the shaft 50 because the auxiliary frame C can move no further.

Since the reaction handle 102 is fixed to the auxiliary frame it also remains stationary and as operating handle 98 pivots upon pin 100, it moves away from the reaction handle 102 so that the latter may be grasped by the operator and during the continued movement of the operating handle 98 in a counterclockwise direction a force may be exerted on this reaction handle 102 opposing the force exerted on the operating handle 98 so as to counterbalance the force applied to form the joint, and relieve the package being bound of operating force communicated thereto by the tool, such as is normally present when a conventional tool is used. This further movement of the operating handle 98, through the link 160, crosshead 156 and links 150 actuates the sealing jaws 140 to deform the seal 200 and the overlapping strap ends to form a joint.

During the sealing operation the ejector blade 234 is moved to the retracted position shown in

Fig. 2 as previously explained and it is held in this position until the operating handle 98 has been pivoted through a sufficient angle in a return direction from the limit of its second range of movement to rotate the cam 248 backwardly far enough to bring its flat radially extending face 256 into line with the tip of screw 250, whereupon the ejector actuator 224 is released for return movement by its spring 232. On the return of the ejector actuator the stripper tip 242 of the ejector blade 234 engages the edge of the forward seal in the magazine and this seal is moved in an endwise direction along the ledges 214 and 216 toward the sealing jaws 140 until its lower end engages the upper surface of the partly opened sealing jaws. The return movement of the handle 98 does not open the sealing jaws sufficiently to receive the seal until the handle has almost completed its return from the second range of movement. During this time the ejector continues to press upon the seal due to the action of spring 232 on the ejector actuator 224. As a result at the instant the jaws 140 open sufficiently to receive a seal, the seal is suddenly snapped into position in the jaws. This will occur just prior to the end of the return movement of the operating handle 98 at which time the latch 112 engages the fixed pin 118. Thus the operator, if he desires so to do, may hold the reaction handle 102 and apply force to the same opposing and counterbalancing the force required to return the operating handle 98 to the position of the fixed relation with the auxiliary frame until just prior to the time that return movement is completed. The handles and auxiliary frame C may then be oscillated until the stop lug 122 engages upon the top of handle 12 formed on the main frame 10.

To release the tool from the bound binder loop the handle 56 is rotated in a clockwise direction, as viewed in Fig. 1, until the pin 72 on the shank 58 engages in the notch 70 in the latch 62. The handle 56 is then released and is held in retracted position by the latch 62. Rotation of the handle 56 as above described rotates the bolt 16 in a direction to cause the eccentrically mounted feed wheels 82 thereon to be raised from the binder ends. At the same time the lug 78 on the cam 58 of handle 56 engages the lug 48 on aligning lever 32 and lifts this lever sufficiently to release the overlapping binder ends and open channel 18. The tool may then be removed from the package by sliding the same laterally until the foot 22 becomes disengaged from under the bound loop. Since the seal was fed to the sealing mechanism during the return movement of the handle, the tool when removed from a package is in condition for a new sealing operation.

Having thus illustrated and explained the nature and an embodiment of our invention, what we claim and desire to secure by United States Letters Patent is as follows:

1. In a package binding tool of the type having a main frame adapted to rest upon a package to be bound and pivotally supporting a binder tensioning mechanism and an auxiliary frame carrying sealing jaws, and an operating handle pivotable with said auxiliary frame through a first range of movement for operating said tensioning mechanism to tension the binder encircling the package being bound and pivotable in the same plane and away from said main frame and with respect to the auxiliary frame through a second range of movement for operating said sealing jaws to form a joint in the overlapping ends of the binder, the improvement which comprises a

reaction handle fixedly secured to said auxiliary frame and pivoting with said auxiliary frame and operating handle through the first range of movement thereof and separable from said operating handle when said operating handle pivots with respect to said auxiliary frame, said reaction handle being adapted to have applied thereto a force in opposition to and counterbalancing the force exerted on the operating handle throughout the second range of movement of the latter to relieve the package being bound of the pressure exerted upon the operating handle, and means for releasably locking said operating handle and auxiliary frame together for movement through the first range of movement aforesaid, said means comprising a pin carried by said operating handle, a latch member pivoted on said auxiliary frame and having a notch therein, said pin being adapted to engage in said notch, and a spring biasing said latch member to pin engaging position, said pin being released from said latch notch when a force in excess of a predetermined maximum is exerted on said operating handle to allow the latter to pivot with respect to said auxiliary frame and reaction handle through the second range of movement.

2. In a package binding tool having a main frame adapted to rest upon a package to be bound and pivotally supporting a binder tensioning mechanism for tensioning a package encircling binder and an auxiliary frame carrying a sealing mechanism for placing a seal over and joining the overlapping ends of the package binder and a seal feeding mechanism, the combination comprising a magazine for storing a stack of seals, an outlet at one end of said magazine, a movable trap door in one wall of said magazine at said outlet, a follower for urging seals toward said outlet, guide means formed in said outlet for holding said seals in said magazine against the pressure exerted thereon by said follower, said guide means being adapted to guide seals one at a time from the bottom of the stack for endwise movement into said sealing mechanism to permit automatic loading of the same by said feeding mechanism when said tool is in use, at least a portion of said guide means being secured to said trap door and said trap door being adapted to be moved to open position to remove at least a portion of the support for the seal to be fed if the seal to be fed becomes jammed in said magazine to permit manual withdrawal of the same therefrom.

3. In a package binding tool having a main frame adapted to rest upon a package to be bound pivotally supporting a binder tensioning mechanism for tensioning a package encircling binder and an auxiliary frame carrying a sealing mechanism for placing a seal over and joining the overlapping ends of the package binder and a seal feeding mechanism, the combination comprising a magazine for storing a stack of seals, an outlet at one end of said magazine, a follower for urging seals toward said outlet, a pivoted trap door forming one wall of said magazine at said outlet, guide means formed in said trap door and the opposing wall of said outlet for holding said seals in said magazine against the pressure exerted thereon by said follower, said guide means being adapted to guide seals one at a time from the bottom of the stack for endwise movement into said sealing mechanism to permit automatic feeding of the same by said feeding mechanism when said tool is in use, said trap door being adapted to be moved to disengage the guide means thereon from the

last seal in the stack if said feeding mechanism becomes jammed to permit manual withdrawal of the jammed seal from said magazine.

4. In a package binding tool having a main frame adapted to rest upon a package to be bound pivotally supporting a binder tensioning mechanism for tensioning a package encircling binder and an auxiliary frame carrying a sealing mechanism for placing a seal over and joining the overlapping ends of the package binder and a seal feeding mechanism, the combination comprising a magazine for storing a stack of seals, an outlet at one end of said magazine, a follower for urging seals toward said outlet, a pivoted trap door forming one wall of said magazine at said outlet, guide means formed in said trap door and the opposing wall of said magazine for holding said seals in said magazine against the pressure exerted thereon by said follower, said guide means being adapted to guide seals one at a time from the bottom of the stack for endwise movement into said sealing mechanism to permit automatic feeding of the same by said feeding mechanism when said tool is in use, said trap door being adapted to be moved to disengage the guide means thereon from the last seal in the stack if said feeding mechanism becomes jammed to permit manual withdrawal of the jammed seal from said magazine, and resilient means for urging the trap door to position the guide means thereon in sealing engaging position.

5. In a package binding tool having a main frame adapted to rest upon a package to be bound pivotally supporting a binder tensioning mechanism for tensioning a package encircling binder and an auxiliary frame carrying a sealing mechanism for placing a channel shaped seal over and joining the overlapping ends of the package binder and a seal feeding mechanism, the combination comprising a magazine secured to said auxiliary frame for storing a stack of said channel shaped seals in nested relation, an outlet at one end of said magazine, a follower for urging seals toward said outlet, a pivoted trap door forming one wall of said magazine at said outlet, longitudinally extending ledges formed in said trap door and the opposing wall of said outlet adapted to engage the flanged edges of the last seal in said stack to retain the same in said magazine against the pressure exerted thereon by said follower, said ledges being adapted to guide seals one at a time from the bottom of the stack for endwise movement into said sealing mechanism to permit automatic feeding of the same by said feeding mechanism when said tool is in use, said trap door being adapted to be pivoted to disengage the ledge therein from the last seal in said stack if said feeding mechanism becomes jammed to permit manual withdrawal of the jammed seal from said magazine.

6. In a package binding tool of the type having a main frame adapted to rest upon a package to be bound and pivotally supporting a binder tensioning mechanism and an auxiliary frame carrying sealing jaws, and an operating handle movable with said auxiliary frame through a first range of movement for pivoting said auxiliary frame and simultaneously operating said tensioning mechanism to tension a package encircling binder and through a second range of movement in the same plane and away from said main frame for swinging said auxiliary frame and sealing jaws into sealing position and thereafter relative to said auxiliary frame for operating said sealing jaws to form a joint in the overlapping ends of

the binder, the improvement which comprises a reaction handle for applying a force to said auxiliary frame throughout the second range of movement of said operating handle counterbalancing the force exerted on the latter and thereby relieving the package being bound of the pressure exerted upon the operating handle while a joint is being formed, said reaction handle being fixed rigidly to said auxiliary frame and positioned to lie against said operating handle during the first range of movement of said operating handle but separating said operating handle when said operating handle moves relative to said auxiliary frame, and releasable latching means including a spring biased latch member pivoted to said auxiliary frame and a pin carried by said operating handle and engageable therewith for securing said two handles in fixed relation during the first range of movement.

7. In a package binding tool for tensioning a package encircling binder having a main frame adapted to rest upon a package to be bound, a binder tensioning mechanism eccentrically secured upon a shaft rotatably journaled with respect to said main frame and normally biased to urge the binder tensioning mechanism to binder engaging position, a transversely extending lever pivoted adjacent one of its ends to the main frame and cooperating therewith to form a guide for overlapping end portions of the binder in one position to hold them in aligned relation during a tensioning operation, and means secured to the shaft for rotating the shaft to move the tensioning mechanism out of binder engaging position, the improvement which comprises a lip on the free end of the aligning lever and projecting angularly therefrom and rearwardly of the tool, and a lug on the means for rotating the shaft and movable therewith to engage the lip to move the lever out of binder aligning position when the tensioning mechanism is moved out of binder engaging position.

8. In a package binding tool for tensioning a package encircling binder having a main frame adapted to rest upon a package to be bound, a binder tensioning mechanism eccentrically secured upon a shaft rotatably journaled with respect to said main frame and normally biased to urge the binder tensioning mechanism to binder engaging position, a transversely extending lever pivoted adjacent one of its ends to the main frame and cooperating therewith to form a guide for overlapping end portions of the binder in one position to hold them in aligned relation during a tensioning operation, and means secured to the shaft for rotating the shaft to move the tensioning mechanism out of binder engaging position, the improvement which comprises a lip on the free end of the aligning lever and projecting angularly therefrom and rearwardly of the tool, a lug on the means for rotating the shaft and movable therewith to engage the lip to move the lever out of binder aligning position when the tensioning mechanism is moved out of binder engaging position, and a shoulder on the means for rotating the shaft and movable therewith to engage the lip to lock the lever in binding aligning position when the tensioning mechanism is moved to binder engaging position.

9. In a package binding tool having a main frame for resting on the package to be bound pivotally supporting a binder tensioning mechanism and an auxiliary frame carrying a sealing mechanism of the type including pivoted sealing jaws for joining together the overlapping ends of

a package binder and movable with the auxiliary frame from a position removed from the binder to a joint forming position, a single operating handle for moving the auxiliary frame and the sealing mechanism to joint-forming position and for actuating the sealing mechanism to engage the seal over the overlapping ends of the binder and the jaws to deform the same for forming a joint therein, and a magazine on the auxiliary frame for the storage of seals used in joining the ends of the binder and having an outlet adjacent the sealing mechanism jaws through which seals may be transferred from the magazine to the jaws, the improvement which comprises an ejector blade at the magazine outlet adapted to engage the outermost seal in the magazine and movable in a first direction to transfer the seal from the magazine to the sealing mechanism, a bell crank lever pivotally mounted on the magazine and having a first arm pivotally connected to said ejector blade, a spring acting between said lever and a fixed part of the magazine for biasing said lever in such direction as to move said ejector blade in the seal transferring direction, a cam engageable with a second arm of said lever rotatably mounted on the magazine and connected to the operating handle for rotation in one direction, while the operating handle is closing the sealing mechanism jaws to form a joint in the overlapping ends of the binder, for moving said lever against the force of said biasing spring to move said ejector blade in a second direction to a position preparatory to transferring a seal from the magazine, said cam being formed to remain in engagement with said lever until the joint has been formed and return movement of the operating handle has been initiated and while in said engagement locking said ejector blade in said second position, and said cam also being formed so that when it is rotated in a second direction it releases said lever during retraction of the operating handle and before the sealing mechanism jaws have been separated sufficiently to receive the seal, whereby a seal is snapped into position in the sealing mechanism under the force of said biasing spring.

10. In a package binding tool having a main frame for resting on the package to be bound pivotally supporting a binder tensioning mechanism and an auxiliary frame carrying a sealing mechanism of the type including pivoted sealing jaws for joining together the overlapping ends of a package binder and movable with the auxiliary frame from a position removed from the binder to a joint forming position, a single operating handle for moving the auxiliary frame and the sealing mechanism to joint-forming position and for actuating the sealing mechanism to engage the seal over the overlapping ends of the binder and the jaws to deform the same for forming a joint therein, and a magazine on the auxiliary frame for the storage of seals used in joining the ends of the binder and having an outlet adjacent the sealing mechanism jaws through which seals may be transferred from the magazine to the jaws, the improvement which comprises an ejector blade at the magazine outlet adapted to engage the outermost seal in the magazine and movable in a first direction to transfer the seal from the magazine to the sealing mechanism, a bell crank lever pivotally mounted on the magazine and having a first arm pivotally connected to said ejector blade, a first spring acting between said lever arm and said ejector blade pivotally connected to the magazine outlet, and a second spring biasing the latter toward the magazine, a second

spring acting between said lever and a fixed part of the magazine for biasing said lever in such direction as to move said ejector blade in the seal transferring direction, a cam engageable with a second arm of said lever rotatably mounted on the magazine and connected to the operating handle for rotation in one direction, while the operating handle is closing the sealing mechanism jaws to form a joint in the overlapping ends of the binder, for moving said lever against the force of said second biasing spring to move said ejector blade in a second direction to a position preparatory to transferring a seal from the magazine, said cam being formed to remain in engagement with said second lever arm until the joint has been formed and return movement of the operating handle has been initiated and while in said engagement locking said ejector blade in said position, and said cam also being formed so that when it is rotated in a second direction it releases said lever during retraction of the operating handle and before the sealing mechanism jaws have been separated sufficiently to receive the seal, whereby a seal is snapped into position in the sealing mechanism under the force of said second biasing spring.

11. In a package binding tool having a main frame for resting on the package to be bound pivotally supporting a binder tensioning mechanism and an auxiliary frame carrying a sealing mechanism of the type including pivoted sealing jaws for joining together the overlapping ends of a package binder and movable with the auxiliary frame from a position removed from the binder to a joint forming position, a single operating handle for moving the auxiliary frame and the sealing mechanism to joint-forming position and for actuating the sealing mechanism to engage the seal over the overlapping ends of the binder and the jaws to deform the same for forming a joint therein, and a magazine on the auxiliary frame for the storage of seals used in joining the ends of the binder and having an outlet adjacent the sealing mechanism jaws through which seals may be transferred from the magazine to the jaws, the improvement which comprises an ejector blade at the magazine outlet adapted to engage the outermost seal in the magazine and movable in a first direction to transfer the seal

from the magazine to the sealing mechanism; a bell crank lever pivotally mounted on the magazine and having a first arm pivotally connected to said ejector blade, a spring acting between said lever and a fixed part of the magazine for biasing said lever in such direction as to move said ejector blade in the seal transferring direction, said lever having a second arm carrying an adjustable cam contacting member which may be adjusted to vary the throw of said lever, a cam engageable with said contacting member rotatably mounted on the magazine and connected to the operating handle for rotation in one direction, while the operating handle is closing the sealing mechanism jaws to form a joint in the overlapping ends of the binder, for moving said lever against the force of said biasing spring to move said ejector blade in a second direction to a position preparatory to transferring a seal from the magazine, said cam being formed to remain in engagement with said cam contacting member until the joint has been formed and return movement of the operating handle has been initiated and while in said engagement locking said ejector blade in said second position, and said cam also being formed so that when it is rotated in a second direction it releases said lever during retraction of the operating handle and before the sealing mechanism jaws have been separated sufficiently to receive the seal, whereby a seal is snapped into position in the sealing mechanism under the force of said biasing spring.
